UNITED STATES PATENT OFFICE.

EDWARD L. MEGILL, OF NEW YORK, N. Y.

FEED-GAGE FOR USE ON PRINTING-PRESSES.

1,324,684.

Specification of Letters Patent.

Patented Dec. 9, 1919.

Application filed March 31, 1919. Serial No. 286,475.

To all whom it may concern:

Be it known that I, EDWARD L. MEGILL, a citizen of the United States, residing at New York, in the county of New York and State of New York, have invented certain new and useful Improvements in Feed-Gages for use on Printing-Presses, of which the following is a specification.

This invention relates to feed gages for use on printing presses, of the general type shown for instance in my Patent No. 241,556 of May 17th, 1881, in which there is a prong for insertion through a hole or slit in a tympan sheet, two arms adapted to overlie the tympan sheet, a vertical head member connecting the prong and the arms, and a tongue projecting through an opening in the head member and having bent portions gripping the edges of the two arms, wherefore the tongue may be slid to different positions along the arms so that it will project more or less through the head member. The hold of the tongue on the arms depends on the resiliency of the parts, and I have found that the tongue will not be firmly held in position at the outer ends of the arms, particularly after the device has been in use for some time. Accordingly, one of the objects of the present invention is to provide a construction in which the two arms aforesaid are arranged so that they diverge from the head member with which they are integral, the distance between the arms adjacent the point where they join the head member being such that when the gripping portions of the tongue are over the edges of the arms adjacent this point, the gripping portions will be firmly held. In other words, the distance between the arms at this point is slightly larger than the distance between the gripping portions of the tongue so that the tongue will be frictionally held. And as the tongue is adjusted to different positions toward the outer end of the two arms the friction is increased because the arms diverge away from the head member. The result of this is that the grip of the tongue on the arms will be at least as great at the outer ends of the arms as at the inner, and this notwithstanding the gradual loss of resiliency due to repeated squeezing

together of the arms in making adjustments or in taking off or putting on new or different tongue members.

A further object of my invention is to provide a device of the kind above referred to which may be readily stamped out of a single piece of suitable material, in which the connection between the prong and head member are decidedly strengthened and stiffened, and in which provision is made for an opening in the head member through which the adjustable tongue may project which opening extends to the lower edge of the head member, though the surrounding edges defining the opening are everywhere unbroken.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of the invention, Figure 1 is a plan view of a feed gage embodying my invention mounted in position on a fragment of the tympan; Fig. 2 is a plan view of the adjustable tongue; Fig. 3 is an end view of the tongue; Fig. 4 is a plan of the blank from which the entire device, except for the adjustable tongue, is formed; Fig. 5 is a bottom plan view of a gage embodying my invention with the adjustable tongue in position; Fig. 6 is an edge view of the same; Fig. 7 is a view looking at the other side of Fig. 5 and showing the tongue in a different adjusted position; Fig. 8 is an end view of the subject-matter of Fig. 7 looking toward the head member; and Fig. 9 is an end view of the subject-matter of Fig. 7 looking at the right-hand end of that figure.

Referring to the numerals on the drawings, there is shown at 10 a prong preferably having a pointed end which is to be

pushed through a hole in the tympan sheet 11. 12 is a head-piece to which the prong 10 is connected, and which head-piece in use is disposed vertically with respect to the 5 tympan sheet. This head-piece has usual extensions symmetrically on opposite sides of the connection with the prong and has backwardly turned wings 14 and downward projections or points 15 which may be forced 10 into the tympan sheet to hold the device in position. Extending backwardly from the head member 12 is a pair of integral arms, which for reasons hereinafter explained, 15 diverge away from each other, beginning with their point of connection to the head member. At their outer ends these arms are as usual provided on their outer edges with cut-out portions 17.

The usual form of adjustable tongue is 20 shown in Figs. 2 and 3 and comprises a tongue proper 18 extending from a cross plate 19 having an upstanding finger part 20 and dependent gripping fingers 21. In use the tongue extends through an opening 25 in the head member, as shown in Fig. 1 for instance, and the tongue is engaged with the arms by slipping the gripping fingers 21 over the arms at the cutouts 17, after which the arms 16 are pressed toward each other 30 so that the gripping fingers may engage the edges of the arms inwardly of the cut-outs 17. Obviously, in order to hold the tongue on the arms the distance between the gripping portions of the tongue should be less 35 than the distance between the outer edges of the arms at any point of their length excepting only the cut-out portions 17, so that the tongue will be held frictionally at any adjusted position along the arms. If the 40 arms were merely parallel, instead of divergent, repeated pressing together of the ends of the arms would tend to destroy their resiliency so that after a time the tongue would not be held firmly if adjusted to a 45 position toward the outer ends of the arms. With the present construction there is always the proper tension to hold the tongue in any adjusted position. Obviously, the inherent resiliency of the gripping fingers 21 is of 50 some assistance.

The opening 22 through the head member 12 is formed in the blank illustrated in Fig. 4 as shown, with its lower edge, which is the one nearest the prong 10, formed on a curve 55 indicated at 24, and the root of the tongue is bifurcated to constitute the edges defining this curved lower part of the opening 22. When the device is formed up from the blank shown in Fig. 4 the prong 10 is bent 60 under the head-piece 12 as shown in Figs. 5 and 6, so that the bifurcations of the prong are at right angles to the head-piece, as is also the curved edge 24. The result of this manipulation is that there is an opening in 65 the head-piece defined by unbroken sur-

rounding edges of the material, which opening extends from top to bottom of the head-piece, so that a tongue 18 projecting through this opening may, if desired, lie flat on the tympan sheet. In addition, it will be seen 70 that the bifurcations of the prong join the head-piece by way of an upward and outward curve, which strengthens the connection between the prong and the head-piece and minimizes the possibility of breakage at 75 this very important point. Obviously, the action upon the metal connecting the prong and the head-piece in inserting the prong through the tympan sheet is to bend the metal along a horizontal line of junctions, 80 and if the bend originally formed at this point were simply in a horizontal line crystallization would take place after a while, with resultant fracture. With my construction however, the original bend of 85 the metal is not in a horizontal line merely but is a twisted bend so to speak which resists crystallization.

It will be understood that the device formed from the blank shown in Fig. 4 is of 90 thin sheet metal of uniform gage throughout, and that the punching out and forming up is done by means of dies in any usual or preferred manner. I find that the form of blank shown in Fig. 4 is very easy to manufacture because the outer edge is struck with 95 a single stroke, simplifying the operation and lessening the cost of manufacture.

I claim:

1. In a device of the kind described, a 100 prong member, an apertured head member integral therewith, divergent arms extending from the head member substantially as and for the purpose described, and a tongue having portions including the outer edges of 105 said arms and extending through the aperture in the head-piece.

2. In a device of the kind described, a 110 prong member, an apertured head member integral therewith, divergent arms extending from the head member substantially as and for the purpose described, the prong member having bifurcations which connect to the head member and define the lower edge of the aperture therein, said bifurcations being disposed at right angles to the head member, and a tongue having portions including the outer edges of said arms and 115 extending through the aperture in the head-piece.

3. In a device of the kind described, a 120 prong member, an apertured head member integral therewith, arms extending from the head member substantially as and for the purpose described, the prong member having bifurcations which connect to the head member and define the lower edge of the aperture therein, said bifurcations being disposed at right angles to the head member, and a tongue having portions including the 125 130

outer edges of said arms and extending through the aperture in the head piece.

4. In a device of the kind described, a prong member and a head member integral therewith, the prong member having bifurcations disposed at right angles to the head member and gradually curved thereinto.

5. In a gage of the class described comprising a head piece and a penetrating prong integral therewith, the line of junction be-

tween the head piece and the prong being on a gradual curve.

6. In a gage of the class described comprising a head piece and an integral penetrating prong the latter having curved 15 bifurcations which connect the prong to the head piece.

In testimony whereof I affix my signature.

EDWARD L. MEGILL.
